FINGERPRINT MACHINE

Harold L. Ballard, Syracuse, N. Y., assignor to
 Misener Manufacturing Co., Inc., Syracuse,
 N. Y., a corporation of New York

Application July 23, 1937, Serial No. 155,169

5 Claims. (Cl. 41—4)

My invention relates to fingerprint machines for use in conjunction with the identification cards now in use by the different bureaus of identification for taking the fingerprints of prisoners, and has for its object a particularly simple and efficient device by the use of which the fingers can be inked and the card held in a plurality of positions for taking the different impressions without harming the card or blurring the impressions.

The invention consists in the novel features and in the combinations and constructions hereinafter set forth and claimed.

In describing this invention, reference is had to the accompanying drawings in which like characters designate corresponding parts in all the views.

Figure 1 is a top plan view of my machine partly broken away and partly in section.

Figure 2 illustrates the card upon which the fingerprints are recorded.

Figure 3 is a side elevation of part seen in Figure 1.

Figure 4 is a vertical sectional view taken centrally of Figure 1.

This fingerprint machine comprises generally, a rectangular shaped body having a base portion extending beyond the ends thereof, a card guide formed in and extending across the upper portions of said body from the front to the back thereof, a guard plate fixed to the top of said body and forming the top of said card guide, an inking plate hinged to the rear portion of said guard plate and overlying the same when in an operative position, and a spring tensioned yoke pivoted to the ends of said body and extending across the front thereof for holding a card in any desired position when in said card guide.

As seen in the drawings the rectangular body 1 is longer than it is wide and is preferably of wood, and the base portion 2 is secured thereto as by screws 3, and extends beyond the sides 4 of said body 1.

The front side 5 of the rectangular body is vertically arranged and the top thereof is formed with a recessed portion 6 extending from the front to the back thereof, and the front portion of said recess 6 is curved to meet the upper portion of the front side 5 as shown at 7 for a purpose to be hereinafter explained.

The recessed portion is covered by a guard plate 8 extending to the ends 4 of the body and from the front side 5 to the back thereof and is fixed to the top thereof beyond the recessed portion 6 as by screws 9.

The recessed portion 6 of the body together with the guard plate forms a card guide extending from the covered front portion 7 to the back of the machine.

The guard plate 8 is cut away from the front side to approximately midway thereof as shown at 10 to expose the card 11 in the card guide as illustrated in Figure 1.

12 is the inking plate, hinged at 13 to the rear portion of the guide plate 8 and arranged to 10 overlie said plate 8 when in its operative position, and 14 are bumpers for supporting the front end of said inking plate 12 when in said position.

The identification cards 11 have one side thereof arranged to have three different series 15 of fingerprints made thereon. The series of spaces A, Figure 2, across the card are for the thumb and fingers of the left hand made separately, the series B are for the thumb and fingers of the right hand made separately, and the series 20 C are for the fingers of the left hand taken simultaneously, the thumbs taken together, and the fingers of the right hand taken simultaneously.

It is obvious that a card of this character has 25 to assume three different positions in the card guide to make the three different series of fingerprints and must be held firmly in each position to prevent smudging the prints.

The means for holding the cards 11 firmly in 30 position in the card guide for each series of fingerprints comprises a spring pressed yoke 15 pivotally mounted at 16 on the ends 4 of the body 1 and extending around the front side 5 thereof. The coiled springs 17, Figure 1, hold the yoke 15 35 against said front side 5.

In use this machine is preferably fixed to the front edge of a desk or table 18 by means of screws through holes 19 in the extended portions of the base plate 2.

The card 11 is first placed in the card guide with the series A spaces exposed to view through the cut out 10 in the guard plate 8, and the bottom portion of the card bent downwardly around the curved portion 7 and held against the front 45 wall 5 of the body 1 by the spring pressed yoke 15 as shown in Figure 3.

The inking plate 12 is put into operative position as shown in Figure 3 with the ink rolled on the side 20 thereof in the usual way.

The fingers are then inked by placing them firmly on the side 20 of the plate 12 and the plate moved to its inoperative position as illustrated in Figures 1 and 4.

The prints of the fingers and thumb of the 55

right hand are then impressed in their respective spaces.

The card is then released by moving the spring pressed yoke 16 by means of the handle portions 5 21 thereon, from the position shown in full lines Figure 4 to that shown in dotted lines, same figure.

This process is repeated for each series of fingerprints.

10 In Figures 1 and 4 the card is shown in position to receive the last, or series C impressions and in Figure 1 said impressions are illustrated in dotted lines.

The guard plate 8 is preferably formed with 15 ribs 22 on the underside thereof and these ribs coact with portions 23 of the card 11 upon which there are no impressions made and prevent freshly inked impressions from being blurred or mussed up by coming in contact with the lower 20 side of the guard plate 8.

The rounded corner 7 prevents the card from being broken when clamped in position by the spring pressed yoke 15 and the extended ends of 25 the base plate 2 provide stops for said yoke when said yoke is in its operative or holding position.

What I claim is:—

1. A fingerprint machine comprising a rectangular shaped body having vertically arranged sides and ends, and a horizontally arranged top, 30 a card guide arranged in the upper portion of said body and extending from said vertically arranged front side to the back thereof, means for holding a card in said guide with the rear end thereof extending downwardly against said front 35 side comprising a spring tensioned yoke extending across the front side of said body for holding said card against said front side.

2. A fingerprint machine comprising a rectangular shaped body, having vertically arranged 40 sides and ends and a horizontally arranged top, a recessed portion in said top extending from the front to the back of said body, a guard plate arranged above said recessed portion, said recess and said guard plate forming a card guide, and 45 an inking plate pivotally mounted on the back of said guard plate and arranged to overlie said guard plate when in its operative or inking position.

3. A fingerprint machine comprising a rectangular shaped body, having vertically arranged 50 sides and ends and a horizontally arranged top, a recessed portion in said top extending from the vertically arranged front side of said body to the back thereof, the front end of said recessed portion being rounded where it meets said vertically arranged front side, a guard plate arranged above 55 said recessed portion, said recessed portion and

said guard plate forming a card guide, means for holding a card in said card guide with the rear end portion thereof extending downwardly around the curved front end of the recessed portion of the card guide and against the front wall of the 5 body comprising a spring pressed yoke pivotally fixed to the ends of said body and extending across the front of the downturned end of said card.

4. A fingerprint machine comprising a rectangular shaped body having vertically arranged sides and ends and a horizontally arranged top, a recessed portion in said top extending from the vertically arranged front side of said body to the back thereof, the front end of said recessed portion being rounded where it meets said vertically arranged front side, a guard plate arranged above said recessed portion, said recessed portion and said guard plate forming a card guide for holding a card in said card guide with the rear 10 end portion thereof extending downwardly around the curved front end of the recessed portion of the said card guide, said guard plate being cut away from the front thereof to approximately midway thereof to expose a portion of 15 the card in the card guide, ribs on the lower side of said guard plate extending from the cut away portion to the back of said plate, means for holding said downwardly extending portion of the card against the front wall of the body comprising a spring tensioned yoke pivotally fixed to the ends of said body and extending across the front wall thereof and across the front of the downturned end of said card; said yoke being 20 operable about said pivots to release said card. 25

5. A fingerprint machine comprising a rectangular shaped body having vertically arranged sides and ends and a horizontally arranged top, a base portion extending beyond the ends of said body portion, a recessed portion in said top extending from the vertically arranged front side of said body to the back thereof, the front end of said recessed portion being rounded where it meets said vertically arranged front side, a guard plate arranged above said recessed portion, said 40 recessed portion and said guard plate forming a card guide, means for holding a card in said card guide with the bottom end thereof extending downwardly against said front wall comprising a spring tensioned yoke pivotally mounted on the 45 ends of said body and extending across said front side, the side arms of said yoke coacting with the base portion of said body when in its operative or holding position and said yoke being operable about said pivots to an inoperative position when the card is released. 50 55
